UNITED STATES PATENT OFFICE.

EDWARD B. CRAFT, OF HACKENSACK, NEW JERSEY, ASSIGNOR, BY MESNE ASSIGNMENTS, TO WESTERN ELECTRIC COMPANY, INCORPORATED, A CORPORATION OF NEW YORK.

TELEPHONE DESK SET.

1,210,424.

Specification of Letters Patent.

Patented Jan. 2, 1917.

Application filed March 2, 1915. Serial No. 11,488.

To all whom it may concern:

Be it known that I, EDWARD B. CRAFT, a citizen of the United States, residing at Hackensack, in the county of Bergen and State of New Jersey, have invented certain new and useful Improvements in Telephone Desk Sets, of which the following is a full, clear, concise, and exact description.

This invention relates to improvements in the construction of telephone desk sets, having for its object the provision of a single, compact and efficient construction in which the condenser and induction coil are mounted within the standard and base respectively of a desk set.

In accordance with this invention there is provided a hollow base having a tubular standard rising therefrom, said standard carrying a transmitter element and switchhook upon its upper portion. A toroidal shaped induction coil is mounted within said base, and a cylindrically shaped condenser is inclosed within said standard. Contacting and switching means are provided for electrically connecting the various telephone elements in the same circuit. A clamping means is also provided for rigidly holding the various elements comprising the desk set, in their respective order of assembly.

The nature and advantage of this invention will hereinafter more fully appear.

This invention is illustrated in the accompanying drawings in which—

Figure 1 is a front elevation, partly in section, of a telephone desk set embodying the features of this invention; Fig. 2 is a plan view of the mounting plate inclosed within the base; Fig. 3 is a detailed fragmentary view of the condenser and means for connecting the same in the telephonic circuit; Fig. 4 is a side elevation of the condenser and spring assembly shown in Fig. 1; and Fig. 5 is a circuit diagram showing apparatus wired in accordance with this invention.

Rising from a pedestal or hollow base 6 is a tubular standard 7 which may be removably mounted in said base by means of retaining ring 8 having interior threads adapted to engage exterior threads formed upon the lower extremity of said standard. The standard 7 has an upset portion 9 formed near its base to limit the movement thereof into the base 6. A transmitter element 10 and a switchhook 11 is carried at

the upper portion of the standard 7. A mounting plate 12 comprising a metallic portion 13 and a non-metallic portion 14 is inclosed within the base 6. Secured to the non-metallic portion 14 are a plurality of contact members 15 which extend toward the center of the base 6. A plurality of binding posts 16 are provided for connecting an extension cord to the desk set. Secured by means of clamps 18, held in position with screws 19, is a toroidal shaped induction coil 17. A toroidal induction coil is used, not only because its shape renders it convenient for mounting in this position, but mainly because its "endless" magnetic circuit practically eliminates a leakage field and the consequent energy loss in the metallic base 6, which would necessarily accompany the use of a solenoidal induction coil. A cylindrically shaped condenser 20 which is supported by the mounting plate 12, extends upwardly into the standard 7. The condenser 20 is provided with a plurality of ribs 21 which terminate at one end in contact members 22 and at the other end in contact members 23. The ribs 21 are preferably positioned so as to be approximately 120° apart thus avoiding the possibility of the contacts carried on their extremities from interfering with each other. The center of the condenser 20 is made hollow so as to accommodate a rod 26, one end of which is threaded, while to the other end thereof there is secured an L-shaped bracket 27. By means of a nut 29, the bracket 27 may be drawn down and rigidly held in position at the upper end of the condenser 20. Any suitable means, such as a lug (not shown in the drawing) punched from the short end of the bracket 27 may be employed to prevent the condenser 20 from rotating. A plurality of contact springs 30 arranged in the form of a spring assembly and secured by means of screws 31, are attached in an upright position to the bracket 27. The switchhook 11 and a mounting piece 45 for the transmitter element 10, is secured in any suitable manner to the upper end of the bracket 27. The contact springs 30 are so positioned as to be in operative relation with the switchhook 11 and make and break contact upon the actuation of said switchhook.

Contact members 23 are connected to the contacts 30 by means of conductors 32. When the condenser 20 and the elements 110

attached thereto are inserted into the standard 7, contacts 22 mutually engage with the contact springs 15 and this structure is held in place by means of a nut 36 screwed upon 5 the portion of the rod 26 which extends through an aperture in the mounting plate 12. A crow-foot 33, mounted intermediate the under surface of the base 6 and the retaining ring 8, furnishes a means by which 10 the mounting plate 12, through the medium of screws passing through apertures 34, may be fastened within the base 6. A receiver 37, when not in use, is supported by the switchhook 11. The opening in the bottom 15 of the base 6 may be closed by means of an annular disk or plate member 38.

The circuit arrangement of the telephonic elements in accordance with this invention may best be understood by reference to Fig. 20 5. The lower part of the figure shows the windings of the induction coil 17 properly connected to the contact members 15 and the binding posts 16. Conductors 40 and 41 are the strands of a two-conductor cord 25 which may be used to connect the desk set with a desk set box, and conductors 42 and 43 connect the receiver 37 to the contact member 15 and binding post 16, respectively. The connection through the condenser 20 is 30 conventionally represented and the contact members of said condenser and the induction coil 17 are relatively represented as occupying the position which they occupy when in engagement with each other. A battery circuit 35 for the transmitter 10 may be traced by the following path: conductor 40, binding post 16, primary winding of the induction coil 17, contact members 15, 22, rib 21, contact member 23, conductor 32, contact springs 30, through the transmitter 10, conductor 32, contact member 23, rib 21, second set of contact members 22, 15, out over conductor 41. The receiver 37 is inductively connected to the circuit just described 40 by the following path: left hand binding post 16, conductor 43, receiver 37, conductor 42, contact members 15, 22, rib 21, contact member 23, conductor 32, through the transmitter 10, middle contact spring 30, 45 conductor 32, contact member 23, condenser 20, second set of contact members 22, 15 secondary winding of the induction coil 17, back to binding post 16.

From the above it will be seen that the 50 general construction of a desk stand, which requires only a two-conductor cord, has been greatly simplified, and a solid, compact structure obtained, in which all of the parts are easily accessible.

60 What is claimed is:

1. In a telephone desk set, a hollow base, a mounting plate inclosed within said base, a toroidal shaped induction coil clamped to said plate, a tubular and removable stand- 65 ard rising from said base, a transmitter ele-

ment and switch-hook carried at the upper portion of said standard, a condenser inclosed within said standard, separable and mutually engaging contact members carried respectively by said mounting plate and said condenser, clamping means for drawing and holding said plate, condenser and contact members together, and means for securing said base and standard together. 70

2. In a telephone desk set, a hollow base, 75 a tubular standard rising from said base, a transmitter element and switchhook carried at the upper portion of said standard, a toroidal shaped induction coil mounted within said base, a condenser inclosed within said standard, means for connecting said condenser and induction coil in the transmitter circuit, means for tightening and securing said elements in a given order within said standard and base, and a clamping means 80 for fastening said base and standard together. 85

3. In a telephone desk set, a hollow base, a mounting plate inclosed within said base, a toroidal shaped induction coil secured to 90 said mounting plate, a tubular standard rising from said base, a transmitter element carried at the upper portion of said standard, means of connection between said induction coil and said transmitter, and means 95 for tightening and holding said elements together when assembled in their proper order.

4. In a telephone desk set, a hollow base, a mounting plate inclosed within said base, a toroidal shaped induction coil clamped to 100 said plate, a tubular standard rising from said base, a transmitter element and switchhook carried at the upper portion of said standard, a condenser inclosed within said standard, a plurality of metallic ribs passing 105 longitudinally through the body of said condenser and terminating in contact members at each end thereof, said ribs serving as connecting links for connecting said condenser and induction coil in the transmitter circuit, 110 and means for tightening and holding said elements together when assembled in their proper order.

5. In a telephone desk set, a hollow base, a mounting plate inclosed within said base, 115 a toroidal shaped induction coil clamped to said plate, a tubular standard rising from said base, a transmitter element and switchhook carried at the upper portion of said standard, a condenser inclosed within said 120 standard, a plurality of metallic ribs passing longitudinally through the body of said condenser and terminating in contact members at each end thereof, said ribs serving 125 as connecting links for connecting said condenser and induction coil in the transmitter circuit, means for preventing the rotation of said condenser, and means for tightening and holding said elements together when assembled in their proper order. 130

6. In a telephone desk set, a hollow base, a tubular standard rising from said base, a supporting plate comprising portions of conducting and non-conducting material in-
5 closed within said base, a toroidal shaped induction coil clamped to said supporting plate, a cylindrically shaped condenser in-
closed within said standard, a rod passing through said condenser and having its lower
10 end threaded and adapted to fit into an aperture formed in said mounting plate, an L-
shaped bracket secured to the upper end of said rod, a contact spring assembly mounted upon said bracket, a transmitter element
15 and switchhook carried at the upper end of said bracket, said contact springs being con-
trolled by said switchhook, a plurality of contact members depending from the lower ends of said condenser, contact springs secured to said mounting plate and adapted to 20
mutually engage said contact members, means for tightening and holding said condenser to said mounting plate, and means for fastening said standard and base together.

In witness whereof, I hereunto subscribe 25
my name this 27th day of February A. D.,
1915.

EDWARD B. CRAFT.
